UNITED STATES PATENT OFFICE.

WILLIAM M. CAVANAUGH, OF NEW YORK, N. Y.

BELTING.

Application filed December 8, 1923. Serial No. 679,284.

My invention relates to an improvement in belting—leather belting in particular, although, as a matter of fact, material other than leather may be employed, if desired.

As is well known, leather belting as at present constructed has certain inherent characteristics which are particularly desirable in the transmission of power, and these characteristics I desire to retain. On the other hand, this type of belting is extremely expensive, owing to the fact that nothing but the very best grade of leather can be used with any degree of satisfaction; in fact, it is well known among manufacturers of leather belting that the leather for this particular purpose must be taken from the center of the hide. Leather from other parts of the hide cannot be used practically owing to the fact that it is not of uniform thickness and in addition stretches greatly and unevenly when in use, making it commercially impracticable for leather belting purposes.

One of the objects of my invention is to provide a belting structure which is practically nonstretchable, but which possesses the flexibility, durability, and tractive properties of leather belting as now constructed.

A further object of my invention is the provision of a structure wherein I can make use of scrap leather, if desired, thereby materially reducing the cost of manufacture.

Broadly, my invention consists in providing a belt of leather or other suitable material—I may use fiber, for example, or very heavy canvas duck—in which I employ a vertebrate or articulated structure which imparts the desired flexibility, both lateral and longitudinal, to the structure, this articulated structure being so arranged as to take practically all of the longitudinal strain on the belt as well, and of such a character that stretching of the belting is prevented. This vertebrate construction enables me to make use of leather of a grade which is not feasible under present practice, without, however, sacrificing the desirable or inherent characteristics of leather belting as now constructed.

While the vertebrate structure may be said to constitute a complete structure in itself, I prefer, for tractive purposes, to face the same with thin leather strips.

In the accompanying drawings I have illustrated several embodiments of my in-

vention, inasmuch as the invention may take a variety of forms.

Referring to the drawings—

Figure 1 is substantially a plan view of an embodiment of the invention; and

Fig. 2 is a section taken on the line 2—2 of Fig. 1.

Referring to the drawings in detail, 2 designates a plurality of transverse flexible members, which may be of leather, for example, these members—which will be herein-after referred to as vertebræ—being permanently attached to each other by connecting members 3 of metal, these connecting members extending longitudinally of the belting. The connecting members 3 are spaced a short distance apart and the members carried by one vertebra are offset or staggered with respect to the connecting members of the adjacent vertebra to permit the ends of the connecting members to overlap, the faces of these members, however, lying in the same plane. The ends of each connecting member are given a reverse bend, as indicated in Fig. 2, to provide a loop portion 4 for receiving a pin or pintle 5 about which the sections of the articulated structure are adapted to pivot. These pins or pintles may be of metal, raw hide, or other suitable material. The bent-over ends of the connecting members 3 are bent up slightly out of the plane of the connecting members and embedded into the face of the vertebræ 2 to thereby hold the members in place. The vertebræ 2, connecting members 3, and pins 5 constitute a vertebrate structure.

Inasmuch as the connecting members 3, if of metal, possess very little tractive properties, I prefer to face one side of this structure with thin leather strips 6 extending longitudinally of the belt, a plurality of strips instead of one wide strip being employed, so as not to destroy the lateral resiliency or yield of the belt which is inherent in my improved structure and desirable in most instances, particularly when used on cone pulleys. If desired, a similar facing can be applied to the other face of the belting as well, such a construction being desirable when the belting is to be used as a twisted belt.

It will be seen from the foregoing that I have provided a belt or belting comprising an articulated or vertebrate structure in which the vertebræ are composed of short strips of leather extending transversely of

the belting and attached to each other by metal connecting members to impart the desired lateral resiliency or yield to the belting structure as a whole, the bent or yield necessary to enable the belting to be passed about a pulley being provided by a hinge connection between the individual vertebræ.

It will be apparent also from the foregoing that scrap leather may be employed for the vertebræ 2, if desired, as the longitudinal strain on the belting is taken up by the connecting members 3, so that there is virtually no stretch of the vertebræ 2 and hence it is immaterial whether the members 2 stretch or not or whether they stretch unevenly or not. The fact that I may use scrap leather is of decided advantage over leather belting as now made wherein, as above pointed out, the best grade of leather must be employed to avoid unequal stretching.

It will be seen also that my improved structure retains the desirable characteristics of leather belting as now constructed so far as its tractive and other desirable characteristics are concerned.

It will be further apparent that I have provided an articulate or vertebrate structure for the purpose of imparting the desired flexibility to the structure as a whole, this construction also enabling me to employ a grade of leather which, for one reason or another, has heretofore not been employed, thereby materially reducing the cost of manufacture. By employing leather for the vertebrate structure the belting can yield both in a direction to enable the same to be carried about a pulley and also laterally. The fact that the leather employed may be of uneven thickness or may possess different stretching characteristics, is immaterial in my improved structures inasmuch as the longitudinal stress on the belting is taken up by the metal connecting members which I have employed throughout.

While I have specifically referred to leather as particularly desirable for use in connection with my improved belting, it is to be understood that, as pointed out

above, other materials may be substituted if desired,—materials like fiber, for example, or a very heavy grade of canvas.

It is obvious also that the details of construction may be varied from that above described within the purview of my invention, and hence I desire not to be limited to the exact details illustrated except by the appended claims.

What I claim is:—

1. Belting comprising leather vertebræ each of which is of a length equal to the width of the belting and extending transversely of the belting, sets of non-extensible connecting members attached to said vertebræ, each set of connecting members comprising a plurality of members lying side by side and extending longitudinally of the belting and transversely of the said vertebræ the connecting members of one set overlapping the adjacent set of connecting members said overlapping ends being given a reverse bend to form loops the ends of which are embedded in the said leather vertebræ and means passing through the loop portions of the overlapping ends of the connecting members to attach the connecting members of one vertebræ to the connecting members of the adjacent vertebræ to provide a non-extensible articulated structure.

2. Belting comprising leather vertebræ each of which is of a length equal to the width of the belting and extends transversely of the belting, metal connecting members arranged in sets, one set being attached to one vertebræ and another set to the adjacent vertebræ, said connecting members extending lengthwise of the belting, and each set comprising a plurality of members lying side by side, means for attaching one set of connecting members to the adjacent set of connecting members to provide a non-extensible, laterally yieldable, articulated structure, and strips of leather attached to one face of said structure and extending longitudinally of said structure.

This specification signed this 4th day of December, 1923.

WILLIAM M. CAVANAUGH.
